UNITED STATES PATENT OFFICE

EMILE MAERTENS, OF PHILADELPHIA, PENNSYLVANIA, ASSIGNOR TO
EDWARD SCHEPPERS AND EMILE SCHEPPERS, OF SAME PLACE.

DESIGN FOR WOVEN FABRIC.

Specification forming part of Design No. **11,559**, dated December 30, 1879; application filed December 8, 1879.
[Term of patent 3½ years.]

To all whom it may concern:

Be it known that I, EMILE MAERTENS, of Philadelphia, Pennsylvania, have produced or invented a new and original Design for a Woven Fabric, of which the following is a specification.

My design for a woven fabric is fully shown in the accompanying drawings, which represent views of three pieces of fabric differing from each other in a certain minor detail referred to hereinafter, but all showing the characteristic feature of the design, which comprises open-work stripes *a* and *b* and closely-woven stripes *d*, arranged in respect of each other as clearly shown.

The stripes *a* and *b* have twisted warps, the stripe *a* being wider and composed of finer warps than the stripe *b*, and the distribution of the wefts in the two stripes being different.

The stripe *d* in Figure 1 is corded, the stripe

d in Fig. 2 has a "satine" effect, and the stripe *d* in Fig. 3 presents a mottled appearance.

These modifications are presented in order to show that the character of the stripe *d* may be varied without affecting the distinctive appearance of the design.

In irrespective of the colors employed, I claim—

The design for a woven fabric, said design comprising the open-work stripes *a* and *b* and closely-woven stripes *d*, all substantially as described, and as shown in and by the accompanying drawings.

In testimony whereof I have signed my name to this specification in the presence of two subscribing witnesses.

EMILE MAERTENS.
